CRUPPER

Stuart B. Swagger, Nashville, Tenn.

Application February 27, 1934, Serial No. 713,209

3 Claims. (Cl. 54—22)

This invention relates to cruppers, and its general object is to provide a crupper that is primarily designed for use in training the tail of a horse, so that it will become set in a graceful curve in minimum time, due to the fact that casual displacement of the crupper or movement of the portion of the tail supported and gripped thereby within or from the same is practically impossible.

A further object of the invention is to provide a crupper that can be maintained in fixed relation for holding the tail accordingly by its application to the latter and the buttocks of the animal.

Another object of the invention is to provide a crupper including a one piece or integral buttocks engaging means and tail support, with a tail bandage bar carried by the latter to provide bandage guards to receive the bandage in a manner whereby it can be easily applied, yet is held against looseness and slippage.

A still further object of the invention is to provide a crupper that is light in weight, to eliminate discomfort, is sanitary, easy to apply, maintains itself relatively firm with respect to the buttocks with the aid of harness, is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a view illustrating the application of my crupper for use.

Figure 2 is a perspective view of the crupper.

Figure 3 is a longitudinal sectional view taken therethrough.

Figure 4 is a rear view thereof.

Referring to the drawing in detail, it will be noted that the base of my crupper consists of a pair of spaced parallel flat like shaped arms 1 and 2 which are enlarged at their rear ends to provide heel portions, while the remaining portions are slightly tapered in decreasing width to the front ends of the arms, as clearly shown in Figure 4 of the drawing.

Formed integral with the arms 1 and 2 so as to provide a one piece structure therewith is the tail support of my crupper. The lower end of the body 3 of the tail support bridges the arms 1

and 2, and is outwardly flared therefrom. It will be noted that the body is not only transversely curved to present a substantially semi-circular formation in cross section, but is likewise longitudinally curved as best shown in Figure 3, and gradually decreases in width from its juncture with the arms 1 and 2, to its outer end as best shown in Figure 4, so as to follow the shape of the tail, in order that it will fit the latter.

The upper edges of the body 3 are rounded and extend into beads 4 which merge into the arms 1 and 2 at their inner ends, while the outer ends of the beads 4 extend into a flange 5 that follows the transverse curvature of the outer end of the body as best shown in Figure 2. Extending from the underside of the body 3 and arranged at spaced relation with respect to each other, as well as following the transverse curvature of the body are webs 6 which together with the flange 5 have formed thereon and centrally thereof, extensions 7 having a bar 8 secured thereto and extending therethrough and which is disposed in spaced relation with respect to the underside of the body as best shown in Figure 3 to cooperate with the body and webs, as well as the flange 5 to provide bandage guides, it being apparent that the bar acts as a guard to hold the bandage which is indicated by the reference numeral 9, associated with the body 3 in a manner which will be presently described.

In applying my crupper for use, it is disposed with the arms 1 and 2 arranged in contact with the upper portions of the buttocks of the animal as shown in Figure 1, with the lower portion of the body engaging the underside of the base of the animal's tail, it of course being understood that the ligaments of the tail are cut prior to the application of the crupper so as to allow the tail to be elevated and supported accordingly as shown in Figure 1. After the crupper has been applied, gauze, bandage or the like is wrapped about the tail and body, and of course is passed through the space between the bar 8 and body. The free end of the gauze may be secured by any suitable means such as adhesive tape and of course the entire bandage may be covered with adhesive tape, with the latter passing between the bar and body, with the result the possibility of the bandage becoming loose or slipping is eliminated.

The arms or wings 1 and 2 are curved longitudinally to follow the curvature of the animal's buttocks as shown in Figure 1 and may be padded and provided with suitable covering 9' of leather or the like, but the remaining portion of the crupper is left uncovered. Secured to the for-

ward ends of the covering 9' are converging strap pieces 10 of a harness for the crupper and the converging strap pieces merge into a back strap 11 or are fixed thereto in any well known manner.

Connected to the heel portions of the arms 1 and 2 and extending laterally therefrom are ring members 12 that have the rear ends of side straps 13 secured thereto, and the side straps and back straps extend to and may be secured to the usual 10 surcingle, not shown. The straps may of course be adjustable and adjustable bridging or supporting straps 14 are provided on the sides of the hangers with the ends thereof secured to the back strap 11 and side straps 13 as clearly shown in 15 Figure 1.

From the above description and disclosure of the drawing, it will be obvious that I have provided a crupper that is made into a single piece with the exception of the bandage bar 8 and 20 preferably from aluminum or other light metal so that the device will not cause any discomfort to the animal, this being especially true in view of the smooth tail receiving channel shaped to fit the tail as shown in Figure 1.

25 The tail fitting channel coupled with the bandage and guides therefor, as well as the fitting relation of the arms 1 and 2 with the buttocks of the animal, provides the means whereby the tail is supported to produce a graceful curve therein, 30 in a manner whereby casual displacement with the aid of the harness is practically impossible, with the result the tail will heal and set in minimum time.

35 The one piece structure and the fact that it is made entirely from metal provides a sanitary crupper in that it can be easily retained in a clean and sanitary condition.

It is thought from the foregoing description that the advantages and novel features of my invention will be readily apparent.

I desire it to be understood that I may make

changes in the construction and in the combination and arrangement of the several parts, provided that such changes fall within the scope of the appended claims.

What I claim is:

1. A crupper comprising a base, a tail support including a body outwardly flared from said base and having its lower end formed thereon, said body being curved transversely and longitudinally and tapered toward its outer end for fitting association with the tail of an animal, a flange extending from the outer end of the body, webs extending from the lower surface of said body, said flange and webs following the curvature of said body, a bar secured to and extending through the webs and flange, and said bar being spaced from the under surface of the body to provide bandage receiving means.

10 15 20 25 2. A crupper comprising a buttocks receiving base including a pair of spaced arms, a tail support having a lower portion bridging the arms and formed thereon to provide therewith a one piece imperforate structure, said tail support being curved transversely and longitudinally and tapered toward its outer end, bandage receiving and guiding means on the underside of the tail support, and a covering for the arms.

3. In a device for training an animal's tail and including a crupper and harness for holding it on an animal, and said crupper comprising a buttocks receiving base including a pair of spaced arms, a tail support having a lower portion extending from and bridging the arms, said support being transversely and longitudinally curved and tapered toward its free end, means extending from the underside of the tail support and following the curvature thereof, and a bar extending centrally through said means and cooperating therewith and spaced from the support to provide bandage guiding and receiving means.
